(57) **CLAIM**

The ornamental design for a double finger ring, as shown and described.

DESCRIPTION

FIG. 1 is a perspective view of a double finger ring showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof from the left of FIG. 2;

FIG. 7 is a side elevational view thereof from the right of FIG. 2;

FIG. 8 is a perspective view of a second embodiment of a double finger ring showing my new design;

FIG. 9 is a front elevational view of FIG. 8;

FIG. 10 is a rear elevational view of FIG. 8;

FIG. 11 is a top plan view of FIG. 8;

FIG. 12 is a bottom plan view of FIG. 8;

FIG. 13 is a side elevational view thereof from the left of FIG. 9;

FIG. 14 is a side elevational view from the right of FIG. 9;

FIG. 15 is a perspective view of a third embodiment of a double finger ring showing my new design;

FIG. 16 is a front elevational view of FIG. 15;

FIG. 17 is a rear elevational view of FIG. 15;

FIG. 18 is a top plan view of FIG. 15;

FIG. 19 is a bottom plan view of FIG. 15;

FIG. 20 is a side elevational view thereof from the left of FIG. 16; and,

FIG. 21 is a side elevational view from the right of FIG. 16.
